UNITED STATES PATENT OFFICE.

JOHN LANGSTAFFE, OF BATTERSEA, ENGLAND; STORY B. LADD ADMINISTRATOR OF SAID LANGSTAFFE, DECEASED.

APPARATUS FOR PREVENTING STEAM-BOILER INCRUSTATION.

SPECIFICATION forming part of Letters Patent No. 443,598, dated December 30, 1890.

Application filed February 10, 1890. Serial No. 339,838. (No model.) Patented in England June 1, 1888, No. 8,003.

To all whom it may concern:

Be it known that I, JOHN LANGSTAFFE, a citizen of Great Britain, residing at Battersea, in the county of Surrey, England, have invented certain new and useful Improvements in Apparatus for Preventing Incrustation in Boilers, (for which I have obtained a patent in England, No. 8,003, dated June 1, 1888;) and I do hereby declare the following to be a full, clear, and exact description of the invention, such as will enable others skilled in the art to which it appertains to make and use the same.

This invention relates to electric devices for preventing incrustation in boilers, kettles, and other vessels in which water is heated; and it consists in the novel construction and combination of the parts hereinafter fully described and claimed.

20 In the drawings, Figure 1 is a plan view of the device, and Fig. 2 is a cross-section through the same.

A is a metallic ring, and B is a disk secured to said ring. The disk B preferably consists 25 of a series of filaments b passed through the ring and bent outwardly all around it in the form of a brush. The disk may, however, be formed in various ways—of laminated plates, for instance—the object being to form a very 30 large surface charged with electricity for the heated water to be brought in contact with and upon which the impurities of the water may be deposited. The filaments of the disk may be of fibrous material and may have metallic wires b' intermingled with them, if desired, to assist in conducting the electricity 35 to all parts of the disk.

C are metallic washers secured upon each side of disk B, and D is a bolt which passes 40 through said washers and through ring A, and secures the filaments of the disk in position.

The ring A and the washers C are made of metals which are adapted to form the positive and negative electrodes of an electric circuit.

For instance, the ring A may be of copper and 45 the washers C of zinc, or the washers C may be of copper and zinc. The small washers c, which form a part of the washers C in the drawings, are the copper portions when the main portions of the washers are of zinc. 50

The device is suspended in the vessel in which the water is heated and an electric current is generated by the impure water between the positive and negative electrodes of the device. The impurities of the water 55 would be deposited upon the extensive surface of the disk or brush if the ring and washers were not made positive and negative electrodes; but the deposition would not be so rapid. The circular form of the disk is not 60 material, as the device can be made of any shape found most convenient.

What I claim is—

1. The combination, with a positive and a negative electrode, of a disk of finely-divided 65 material secured between the said electrodes and adapted to be suspended in the water-space of a boiler, substantially as and for the purpose set forth.

2. The combination, with a metallic ring, 70 of a disk secured thereto and consisting of finely-divided filaments having metallic wires intermingled therewith, and metallic washer-plates secured upon the opposite sides of said disk and ring, the said ring and plates being 75 electrodes of opposite polarity, and the whole device being adapted to be suspended in the water-space of a boiler, substantially as and for the purpose set forth.

In testimony whereof I affix my signature in 80 presence of two witnesses.

JOHN LANGSTAFFE.
